Fig. 2

UNITED STATES PATENT OFFICE.

HURLEY G. SMITH, OF PHILADELPHIA, ASSIGNOR TO THE DANVILLE STOVE AND MANUFACTURING COMPANY, OF DANVILLE, PENNSYLVANIA.

DESIGN FOR A STOVE.

SPECIFICATION forming part of Design No. 16,940, dated October 12, 1886.

Application filed August 30, 1886. Serial No. 212,262. Term of patent 7 years.

To all whom it may concern:

Be it known that I, HURLEY G. SMITH, of Philadelphia, in the county of Philadelphia and State of Pennsylvania, have invented and produced a new and original Design for a Stove, of which the following is a specification, reference being had to the accompanying drawings, forming a part thereof.

Figure 1 represents a front view of a stove embodying my new and original design, and Fig. 2 is a side view of the same.

The stove is generally of square form in horizontal section.

The leading feature of my design consists in the stove having scroll and leaf ornamentation of a rustic pattern.

The feet A of the stove are ornamented by the figure of a beaver, *a*, and the skirting B around its bottom by leaves and blossoms *b*. The lower base portion, C, and upper portion, D, are ornamented by embossed beadings *c*, and the top or crown D is represented as supported by long embossed columns *d*, of lattice-like ornamentation, mounted by figures *e*, representing Egyptian faces. The doors E are ornamented on their faces by rustic-work *f*. The center piece or surface between the doors is embellished by scroll-work *g* in imitation of carving. The back section, F, of the stove is decorated by ornaments in intaglio, including a festoon-like border ornament, *h*, and the base portion C is embellished on its sides with a panel, *i*, having a floral ornamentation, *k*. The top of the stove has on it a rustic partly-bower-like ornament, *l*, inclosing a figure, *m*, resembling a beaver, and the name-plate G is of a helmet-like configuration, with a scroll-like ornament, *n*, on its face.

I claim—

1. In a design for a stove, the leg having thereon the representation of a beaver and ornamental work below the same, as herein shown and described.

2. In a design for a stove, the skirting B of the base of the stove herein shown and described, the same consisting of facial ornaments *b*, resembling leaves and blossoms, as shown and described. 45

3. In a design for a stove, the lower base portion, C, upper portion, D, ornamented by embossed beadings *c*, and the intermediate embossed columns, *d*, having figures *e*, representing Egyptian figures, on their tops, as shown and described. 50

4. In a design for a stove, the doors E of the stove herein shown and described, the same consisting of rustic-work ornamentations *f*, as shown and described. 55

5. In a design for a stove, the panel between the doors embellished by leaf and scroll-work figures *g*, as herein shown and described. 60

6. In a design for a stove, the back section, F, embellished by border ornaments *h* in intaglio, of festoon-like configuration, on its borders, as shown and described. 65

7. In a design for a stove, the base portion C, embellished on its sides, as herein shown and described, with a panel, *i*, having a floral and scroll ornamentation, *k*, as shown and described. 70

8. In a design for a stove, the top of the same embellished by a rustic ornament, *l*, inclosing a figure, *m*, resembling a beaver, as herein shown and described.

9. In a design for a stove, the name-plate G, 75 of helmet-like configuration, and embellished, as herein shown and described, with a scroll-like ornament, *n*, and a medallion below the same, as shown and described.

HURLEY G. SMITH.
